UNITED STATES PATENT OFFICE

146,429

DESIGN FOR A GAMEBOARD

Earl Edwards, Monrovia, Calif.

Application February 12, 1946, Serial No. 126,491

Term of patent 14 years

(Cl. D34—5)

To all whom it may concern:

Be it known that I, Earl Edwards, a citizen of the United States, residing at Monrovia, in the county of Los Angeles and State of California, have invented a new, original, and ornamental Design for Gameboard, of which the following is a specification, reference being had to the accompanying drawing, forming part thereof.

The figure is a top plan view of the gameboard embodying my new design, the board being flat and of conventional thickness.

I claim:

The ornamental design for a gameboard, as shown and described.

EARL EDWARDS.
